UNITED STATES PATENT OFFICE

JOHN A. JOHNSON, OF NEW YORK, N. Y.

ASSEMBLING APPARATUS FOR RECEPTACLE CLOSURES

Application filed March 3, 1928. Serial No. 258,777.

This invention relates to assembling apparatus for receptacle closures of the type commonly termed "crown caps", embodying a cap having the marginal portion of the flange arranged with corrugations or ruffles and a sealing disk or pad of suitable material, such as cork, adhesively retained therein, and it is the primary object of the invention to provide improved apparatus of this character to increase the production of closures and to provide apparatus for this purpose which is novel, compact in structure and highly efficient in use.

The present invention relates to closures assembling apparatus of the type disclosed by Letters Patent No. 1,134,031, issued March 30, 1915, and it is an object of the invention to improve the construction and arrangement of such apparatus to increase the capacity thereof without materially increasing the structural cost and without the necessity of increasing the number of attendants in the operation of the apparatus.

In carrying out the invention there are provided parallel channels arranged to support the closure caps at the corrugated marginal portion of the cap flange with means to advance the closure caps intermittently along the channels, means being arranged at one end of the channels and operative in sequence with the cap advancing means for feeding closure caps to the channels. Means are arranged in superposed relation to said channels relative to which the caps are advanced and operative in timed sequence with the advancing movement of the caps to sever disks from adhesive carrying webs and deliver such disks to the caps, and to deliver sealing pads or disks of cork or the like to the adhesive disk carrying caps from stacks arranged at opposite sides of the channel, the caps in the interim of delivery of the adhesive disks and of the sealing disks thereto being passed through a zone having an elevated temperature to render viscous the adhesive carried by the disks. The caps with the sealing disks assembled therein are delivered from the channels to a shelf forming part of a rotatable head carrying plunger adapted to engage and hold the sealing

disks in the caps on the shelf with a yielding force against the viscous rendered adhesive during the period of the cooling and congealing of the adhesive, and means being provided relative to the head for engagement therewith of projections extended laterally from the plungers during a predetermined portion of rotation of the head to move and retain the plungers away from the closure receiving shelf to permit of the delivery of caps with sealing disks assembled therein from the channels to said shelf and the ejecting of closures from the shelf.

In the drawings accompanying and forming a part of this application, Figure 1 is a plan view of receptacle closure assembling apparatus illustrating an embodiment of my invention.

Figure 2 is a sectional view taken on the line 2-2 of Figure 1 looking in the direction of the arrows and partly broken away.

Figure 3 is a perspective view of the right hand end portion of the apparatus shown in Figure 1 and showing the means for feeding closure caps to the cap supporting channels.

Figure 4 is a sectional view taken substantially on the line 4-4 of Figure 3 looking in the direction of the arrows.

Figure 5 is a sectional view taken on the line 5-5 of Figure 1 looking in the direction of the arrow and shows the arrangement of the means for severing disks from adhesive carrying webs and the delivery of the severed disks to caps in the channels.

Figure 6 is a sectional view of the adhesive carrying web feeding means.

Figure 7 is a perspective view of the adhesive carrying web feeding means and the arrangement thereof relative to the cap supporting channels.

Figure 8 is a perspective view of the means for engagement by the caps in a channel for controlling the feeding means for one of the webs.

Figure 9 is an end elevation looking at the right of Figure 1 to show the arrangement of the plunger carrying head.

Figure 10 is a cross sectional view to show the mounting of the plungers in the carry-

ing head and the engaging of the plungers with assembled closures on the shelf of said head to which the assembled closures are delivered from the channels.

5 Figure 11 is a sectional view taken on the line 11—11 of Figure 1 looking in the direction of the arrows.

10 Figure 12 is a plan view to show the arrangement of the actuating means for the sealing disk feeding means shown in Figure 11.

15 Figure 13 is a plan view of the right hand end portion of the apparatus to show the means for positioning caps relative to the cap supporting channels and the means for feeding the caps thereto.

20 Figure 14 is an end elevation of the means shown in Figure 13 for positioning caps relative to the cap supporting channels.

25 Figure 15 is a plan view, on an enlarged scale, of the sealing disk delivery means and showing the means for positioning the assembled closures on the closure receiving shelf of the head relative to the plungers as they are delivered from the channels.

Figure 16 is an elevational view looking at the bottom of Figure 15.

30 Figure 17 is a perspective view of a finger for positioning the caps relative to the plungers as they are delivered from the channels, and Figure 18 is a perspective view of means for guiding the cap delivered from a channel to the closure receiving shelf relative to a plunger.

35 In the embodiment of the invention illustrated the operative mechanism is supported upon a table T mounted adjacent opposite ends upon standards S. A pair of rails 15, 16 is mounted upon the table to extend 40 longitudinally of and in spaced relation to the table by means of brackets D of arch form, each of said rails constituting the outer member respectively of channels A, B, and an intermediate rail 17 constituting the other member of said channels, the edges of said channel rails being preferably beveled to incline in a direction from the top into the channels, as at 18, for the engagement of and serve as supporting ledges for the 45 laterally extending portions of corrugations or ruffles arranged at the margin of the flanges of closure caps C with the cup portion of the caps extended into or through the channels.

50 55 Means are provided to intermittently advance the caps predetermined distances along said channels and to feed caps to one end of the channels. For this purpose there is provided at the one end of the channels, 60 constituting the entrance ends, a disk or table 19 fixed to a vertical shaft 20 to rotate therewith in a horizontal plane in the direction indicated by the arrow in Figure 1 and in a plane with the 65 channel rails, said shaft being rotatably

mounted in the table T and rotated from a drive shaft 21 by a bevel pinion 22 fixed to the shaft 20 meshing with a bevel gear 23 on the shaft 21. The shaft 21 is rotatably mounted in the standards S and in hangers 70 24 fixed to and extending downward from the table T. The cap members of the closures are contained in a hopper (not shown) from which they are delivered to the disk 19 by a chute 25 (Figure 1) leading from the hopper to the disk, the caps as they are discharged from the chute being positioned by the rotation of the disk in alined relation with the leading cap in engagement with a stop 26 (Figure 3) fixed to and constituting a part of a guide plate hereinafter described, and said leading cap and the alternate cap positioned at the entrances to the channels A, B and in line with a pair of plungers 27, with the cap succeeding the leading cap in line with an extension 28 of the intermediate channel rail 17. The plungers 27 are slidably mounted in slideways in a shelf 28' (Figures 3 and 4) carried by posts 29 fixed to and extending upward from the table T with the shelf extending over and spaced from the cap receiving disk 19, the plungers being retained in the slideways by shouldered studs 30 to which the plungers are fixed, the studs being extended through slots in the shelf and plates 31 fixed to the shelf, the plungers being yieldingly urged in a direction to deliver the leading and alternate caps from the cap receiving disk into the channels by springs 32 connected to pins fixed in the supporting bracket D for the channel forming rails and the shouldered studs 30, with abutments in the form of plates 33 secured upon the studs in superposed relation to the plates 31. The plungers are positioned against the force of the springs 32 to permit of the closure caps being positioned by the disk 19 between the ends of the plungers and the entrances to the channels by a block 34 extending transversely of the plates 30 and forwardly of the abutment plates 33, and mounted on a slide 35 mounted in a slideway in the shelf 28' in interposed relation to the plungers 27 by the reduced end of a stud 36 (Figure 4) 105 extended above the block and through a slot in an arm 37 fixed to a stud 38 rotatably mounted in a perforation of a boss of shelf 28. The arm 37 is actuated to move the plungers to the position shown in Figure 3 110 and moved in a direction forwardly thereof to permit the plunger to have cap feeding movement imparted thereto by the springs 32 through the operation of a pair of bars 39, 40, hereinafter described, by connecting the arm carrying stud 38 with the bar 40 by means of an arm 41 fixed to said bar and connected by a link 42 with an arm 43 fixed to stud 38 and extending below the disk 19. To guide and position the caps delivered by 115

120 125 130

the chute to the cap receiving disk 19 between the entrances to the channels and plungers 27 a plate *d* is secured by a thumb screw *e* to the extended end of one plate 31 as shown in Figure 14, to extend from and in the plane of the shelf 28' to the channel rail supporting bracket D shown in Figure 3, the underside of said plate *d* being arranged with a guide ledge *f* in line with the chute 25 by providing the plate with an undercut portion, and the stop member 26 being secured to said undercut portion of the plate at the end opposite to the juncture thereof with the chute 25.

The bars 39, 40 are arranged below the channel forming rails 15, 16 and have elongated plates 44, 45 fixed thereto with a marginal portion in interposed relation to the bars and said channel rails, the plates being of greater width than the bars and the marginal portions opposite to that at which they are secured to the bars extending beyond the one side of the bars and arranged with equidistantly spaced fingers 46, the spaces between the fingers being slightly greater than the diameter of the closure caps. The bars 39, 40 are supported adjacent opposite ends by pivotally connecting the same to disks 48 (Figure 11), as at 47, (Figure 1) eccentric to the axis of said disks, and the disks are fixed to the upper ends of vertical shafts 49 rotatably mounted in bearings in brackets 50 supported from the underside of the table T, the shafts being rotated in synchronism by bevel gears 51 on said shafts meshing with bevel gears 52 on shafts 53 journaled in bearings in the brackets 50 and driven from the drive shaft 21 by a gear 54 on said latter shaft meshing with pinions 55 fixed to the shafts 53. The eccentric connection of the bars 39, 40 with the shafts 49 is such that the finger plates will be moved simultaneously laterally of the channel rails 15, 16 and out of the channels A, B, then longitudinally in a direction toward the cap receiving disk 19, then laterally into the channels to engage the fingers of the plates 44, 45 in the rear of successive caps supported in the channels, and then forwardly of the cap receiving disk 19 to advance the caps in the channels, when the sequence of operation is repeated. By the connection of the actuating arm 37 for the cap feeding plungers 27 with the one bar 40 said plungers will be operated in timed sequence with the finger plate carrying bars to deliver caps from the disk 19 to the channels during the period that the finger carrying plates are moved out of the channels and retrograde movement is being imparted thereto in a direction toward the cap receiving disk 19.

As the caps are advanced along the channels they are successively positioned relative to means for supplying an adhesive to the

caps to secure sealing pads or disks therein. This adhesive is carried by webs in a non-viscid state by coating or impregnating the webs with the same, disks being severed from the webs and deposited in caps in the channels. For this purpose a pair of rolls of adhesive carrying webs W are rotatably supported upon a shaft 57 carried by arms 58 extending laterally from a bracket 59 mounted upon the table T to extend transversely above the cap receiving channels adjacent to the entrance ends thereof (Figures 1 and 7), said brackets having guideways 60 in the upper surface for the webs and the guideways having openings 61 therethrough, one in line with the channel A and the other in line with channel B, and relative to which openings punches 62 are vertically movable to cut disks from the webs and deposit them in caps positioned relative thereto in the channels. These punches are threaded into a head 63 and secured in adjusted position by lock nuts, as shown at 64, the punches slidably engaging openings in a block 66 fixed upon the bracket 59 to guide the same to the openings in the web guideways. The punch carrying head 63 is mounted to have vertical sliding movement and is reciprocated in timed sequence with the advancing of the caps in the channels by rods 67 fixed to the head and extended through the channel rail 17 and table T (Figure 5) and connected below the table to a head 68 having a pivotal connection with an arm 69 extended laterally from a collar or strap 70 encircling an eccentric 71 fixed to the drive shaft 21.

The webs are fed in the guideways relative to the punches by feed fingers in the form of blocks 71^a loosely mounted on a rod 72 extending transversely above the guideways and fixed in upwardly extending arms 73 of a slide 74 slidably mounted on a part of the bracket 59 extended laterally of the table T, the web engaging portion of the blocks being preferably arranged with a friction member, such as a rubber block 71^b (Figure 6), and yieldingly urged into engagement with the webs upon the guideways by springs 75, the webs being guided to said feed fingers between oppositely flared guide plates 75' fixed to the bracket 58. The feed fingers are reciprocated from an eccentric 76 fixed to the drive shaft 21 (Figure 5) having a strap or collar 77 encircling the same connected with the slide 74 by a lever 78 pivotally supported by an arm 79 extended laterally and downward from the bracket 59, said lever having a bifurcation at one end for engaging a rod 80 fixed in ears of the slide 74, as at 81 in Figure 5. The other arm of the lever is adjustably connected with the eccentric strap 77 by a rod 82. To prevent retrograde movement of the webs by the return movement of the feed

fingers pawls 83 are loosely mounted on a rod 84 fixed in brackets 85 mounted upon bracket 59, said pawls having plates 86 fixed to and extended beyond the pawls with the extremities serrated and adapted to engage upon the webs in the guideways. The pawls are retained in position with the serrated plates engaging the webs by weights adjustably mounted on pins fixed in and extending forwardly of the pawls, as at 87 in Figure 7. The pawls are arranged on the rod 84 to rest upon the webs at an angle inclined forwardly to the vertical and as the webs are advanced by the feed fingers they will readily pass below said serrated plates. However, should return movement be imparted to the webs such movement will cause the serrated fingers to forcibly impinge against the webs and hold them against movement.

Means are provided to render the feeding fingers inoperative to feed the webs should there be no caps positioned relative to the punches. For this purpose latches 88 are pivotally supported in blocks upon the bracket 59 to have movement in a direction toward and away from the feed fingers and into and out of the path of movement of pins 89 extending laterally from said fingers, the latches having a weighted lateral extension 90 to normally move the latches to position out of the path of movement of the finger pins 89. The latches are positioned for the supporting and riding of the feed finger pins thereover and thus hold said fingers out of engagement with the webs on the guideways by means controlled by caps positioned in the channels, and comprises a pair of weighted levers 91 pivotally mounted on opposite sides of the bracket 59, one arm of the levers extending below the extensions 90 of the latches and carrying a set screw 92 for the engagement of said latch extensions. The feed finger 71^a feeds the one web to the punch positioned relative to the channel A, and the weighted end of the lever 91 for actuating the latch 88 associated with said feed finger terminates in line with the channel A and is arranged with a weighted contact piece 91' (Figures 5 and 6) for engagement by caps advanced along the channel A, and as said contact piece is engaged by a cap it will lower the end of the lever engaged below the latch extension 90 permitting the latch to move laterally out of the path of movement of the pin 89 carried by the feed finger and permit the finger to be impinged against the web by its spring 75 during the feeding movement thereof and feed the web to the punch. However, should there be no cap in the channel A relative to the weighted end of the lever and thus said end of the lever unsupported by a cap in the channel the lever will move 60 downwardly and elevate the opposite end of

the lever engaging the set screw 92 carried thereby with the latch extension 90 and move the latch into the path of and for engagement by the feed finger pin 89 and thus support the feed finger 71^a out of contact with the web and render the same inactive to feed the web during the movement thereof.

To actuate the latch 88 to render the other feed finger 71^a inactive a contact piece or finger 94 is fixed to and extends laterally from a weighted lever 95 pivotally supported on the bracket 59, as at 96, the contact piece being arranged to extend longitudinally of the channel B and positioned in the path of movement of caps advanced along said channel. Should there be no cap in the channel to engage said contact finger 94 the free end of the lever 95 will move downward moving with it the end of lever 91 to an extension of which lever it is connected by a rod 97 (Figure 7) moving the latch 88 associated with the feed finger 71^a to position for engagement with the pin 89 carried by said feed finger and maintain the latter out of operative relation to the web. When the contact finger 94 is again engaged by a cap in the channel B the lever 95 will be rocked to move the set screw carrying end of lever 91 to permit the latch 88 to move out of the path of movement of the pin 89 of feed finger 71^a and thus rendering the same active to feed the web upon the actuation of said finger. It will be obvious that by the mechanism described that either of the web feeding means is rendered inactive should there be no cap in the channels to be positioned to receive disks severed from the webs by the punches and that such condition of the mechanism will be maintained until there are caps in the channels to receive disks severed from the webs.

The caps are advanced in the channels from the adhesive supplying means to means to deliver sealing disks or pads of suitable material, such as cork, to the caps. For this purpose sealing disks in stack formation in tubular chutes 99 are supported upon members 100 mounted on the table T to extend transversely above the channels from opposite sides of the table in line with slideways 101 in said members, the tubes being fixed at the outer sides of the channels in blocks 102 fixed upon said members 100 with the lower ends of the tubes in spaced relation to the slideways. Ejector plates 103 are slidably mounted in the slideways of the members 100 the forward ends of which ejector plates have a bifurcation therein of arcuate form for engaging and moving the lowermost disk from the stacks and position the same relative to plungers 104 in line with the channels for delivering the disks from the ejectors and depositing them into caps in the channels in line with the plungers 105.

ers. The ejectors are actuated by slides 105 also slidably mounted in slideways in the members 100, said slides being reciprocated by levers 106, pivotally carried by supports 107 for the members 100 and the levers 106 rocked to move the slides toward and away from each other in synchronism with the movement of the cap advancing finger bars 39, 40, by a pair of eccentrics 108, 109 operatively connected with the levers by straps 110 embracing said eccentrics (Figure 11) adjustably connected by rods 110 with the levers 106. As the slides 105 are moved toward the channels a shoulder of the slides 105 engages with the ejector plates and imparts disk engaging movement thereto, and return movement is imparted to the ejectors by latches 111 pivotally carried at 112 on the ejectors engaging the rear of the slides 105. To prevent actuation of either of the ejectors and the ejection of sealing disks from the stacks should there be no caps in either of the channels to receive such disks means are provided to render said ejectors inactive. This means comprises levers 113 pivoted to the side of the members 100, the one arm of the levers being weighted and arranged to extend over the channels and having a contact piece 114 secured thereto adapted to engage in the path of movement of the caps in the channels, the levers being moved for engaging said contact piece in the paths of movement of the caps advanced in the channels for contact by said caps by gravity and the influence of springs 115 seated in a recess in the members 100 and engaging below the extended ends of members 116 fixed upon the latches 111 extended below and with which the ends of the levers 113 opposite to the contact pieces engage, said springs also serving to move and maintain the latches 111 out of operative relation with the slides 113. With caps in the channels the contact pieces 114 will be engaged by said caps as they approach the sealing disk feeding means moving the levers against the force of gravity and the influence of the springs 115, and through the engagement of the levers with the members 116 will position and maintain the latches in operative connection with the slides 105 to impart return movement to the ejectors. However, should there be no caps in the channels the weighted ends of the levers will drop into the channels moving the opposite ends away from the latch members 116 and the springs 115 operating to move the latches 111 out of engagement with the slides 105 releasing the ejectors therefrom. The plungers 104 are carried by a head 117 slidably mounted at opposite ends in uprights 118 fixed in and extending upward from the table T and connected at the upper ends by a crossbar. The plunger carrying head and thereby the plungers are recipro-

cated in timed sequence with the advancing of the caps in the channels and the delivery of sealing disks to the plungers by the ejectors by an eccentric 119 on the shaft 21 connected with the plunger carrying head by an arm 120 extended laterally from a strap 121 encircling the eccentric 119 and pivotally connected with a head 122 below the table T connected with the plunger carrying head 117 by rods 123 extended through openings in the table.

During the interim of the movement of the caps in the channels from the supplying of the adhesive carrying disks thereto and to position for supplying sealing disks or pads to the caps the adhesive is rendered viscous by passing the caps with the adhesive carrying disks therein through a zone having an elevated temperature by passing the caps over the flames from gas jets provided by perforated pipes 124 connected in a suitable manner with a source of supply.

The caps with the sealing disks assembled therein are delivered from the channels to means to place the sealing disks under pressure during the period of cooling or congealing of the viscous rendered adhesive. For this purpose there is provided at the delivery ends of the channels a head mounted on the table to rotate about a vertical shaft 125 fixed in the table and an arm 126 fixed to the end of the table and extended upward and in overhanging relation to the table. The head has an anti-friction support upon the table T comprising balls engaging in raceways in rings fixed upon the table and to the bottom of an annular shelf or table 130 constituting a part of the head, as at 144 in Figure 2. The head is rotated by a pinion 127 meshing with a gear 128 constituting a part of the head, the pinion being driven by a bevel gear on shaft 21 meshing with a bevel gear fixed to the shaft of pinion 127, as shown in dotted lines at 129 in Figure 1. The shelf or table 130 is in a plane with but slightly below the plane of the channel rails to receive the caps as they are delivered from the channels. Two concentric rows of plungers 131, 132 are slidably mounted in openings of rings 133 forming a part of the head arranged in supervised and spaced relation to the shelf and one relative to the other, with the plungers of a length to extend beyond the rings, and normally urged to engage the shelf by springs 134 coiled about the plungers and confined between the bottom of the upper ring and pins 135 fixed in and extending laterally from the plungers.

To position the plungers away from the shelf 130 against the action of the springs 134 to deliver caps on the shelf from the channels and position the same for engagement of the sealing disks therein by the

plungers, a pair of cam plates 136, 137 is provided. The plunger carrying head rotates in the direction indicated by the arrow in Figure 1 and these cam plates are arranged at one side of and to extend beyond the channels for engagement and riding up said cam plates of rollers mounted on studs extending laterally from the plungers, as shown at 138. The cam plates are mounted 5 in superposed relation on posts 139 fixed in a bracket 140 mounted upon the table T to have adjustment relative to the plungers by engaging the reduced ends of the posts in slots in the cam plates, as shown at 141 in 10 Figures 1 and 2. The plungers of the inner row are of greater length than the plungers of the outer row and extend above the same, and the cam plate 136 is arranged to extend beyond the cam plate 137 for the engagement 15 of the rollers carried by said inner row of plungers, and the cam plate 136 being of less length than the cam plate 137. The cam plates are secured in adjusted position by nuts threaded onto the mounting posts 20 139 and the rotation of screws 142 rotatably mounted in and held against longitudinal movement in an extension 143 of the bracket 140 and having threaded connection with ears extended laterally from the cam plates, 25 as clearly shown in Figures 1 and 2.

The caps with sealing disks assembled 30 therein from the channel A are positioned on the shelf relative to the inner row of plungers 132, and for this purpose the channel rail 15 is extended over the shelf to a position slightly beyond the inner row of plungers 132 (Figure 15), and has a plate 145 fixed thereto to extend slightly over the beveled edge 18 of the rail to engage a marginal portion of the cap flange and retain 35 the cap in position on the rail. A finger 146 is pivoted upon said channel rail to extend laterally thereof and urged to a predetermined position toward the channel rail 15 40 in engagement with the stop 145' on the plate 145 by a spring 147 to position a groove extending about the side and ends of a protuberance at the under side and outer end of the finger, as at 148, in line 45 with the bevel edges 18 of the channel rails 15, 17 to receive and engage a cap as it is delivered from the channel at the marginal portion opposite to the engagement thereof by the rail 15, and thus co-operate with the 50 plate 145 to position a cap in line with a plunger 132 for engagement by the plunger as it rides off from the cam plate 136. As the cap on the shelf is engaged by a plunger and is moved with the plunger and shelf by 55 the rotation thereof it will move the finger 146 against the tension of the spring 147, and as the finger rides off from the cap it will again be positioned relative to the stop pin 145' by said spring. 60

65 To position caps delivered from the chan-

nel B relative to the plungers 131 a finger 149 is fixed upon the channel rail 17 to extend beyond the end of said rail with the extremity curved in a direction into the channel, as at 150, said finger having a 70 groove in the edge in line with the bevel edge of the rail 17 and cut through the curved extremity for engagement of the marginal portion of a cap. The cap is retained in position relative to the plate 75 groove by a finger 151 pivotally mounted at one end on the plate 149 and urged in a direction toward the channel rail 16 by the spring 147 to position a groove extended about the side and ends of a protuberance 80 at the under side of the outer end, of the finger, similar to the protuberance on the finger 146, as at 151; in line with the beveled edge 18 of rail 16 and in opposed relation to the groove in the plate 149 for the 85 engagement of the marginal portion of a cap as it is delivered from the channel and thus position a cap delivered from channel B on the shelf relative to and for engagement by a plunger 131 as the plunger rides 90 off from the cam plate 137. As the cap delivered from the channel B to the shelf is engaged by a plunger it is moved with the plunger and shelf by the rotation thereof of moving the Finger 151 against the tension of the spring 147, and as the finger rides off from the cap it will again be positioned 95 relative to the stop pin 152 by the spring 147. To permit the finger to move sufficiently for the passage of the cap on the shelf the end of the rail 16 in the rear of the cap supporting edge is cut away, as 100 shown at 15.

As the plunger rollers 138 ride up the cam plates to position the plungers away 105 from the shelf and release the plungers from the closures upon the shelf an ejector bar 153 intersecting the row of closures positioned on the shelf relative to the plungers 132 is engaged by said closures and along 110 which bar such closures are moved by the rotation of the shelf with the head to eject such closures from the shelf, said ejector bar being fixed to a bracket 154 fixed to the cam plate carrying bracket 140. The closures positioned on the shelf relative to the plungers 131 are ejected by a bar 155 carried by a plate 156 fixed upon the bracket 154 to extend above the ejector bar 153 whereby the closures ejected by said latter 115 bar may pass below said plate.

The apparatus is driven from a shaft 157 journaled in hangers 158 suspended from the under side of the table T and said shaft connected with the drive shaft 21 by bevel 120 gearing 159. The shaft 157 has a pair of pulleys thereon, one of which is fixed and the other loose to belt drive the shaft from a suitable source of power.

It will be obvious that various modifications

tions may be made in construction and arrangement of parts without departing from the scope of the invention.

Having thus described my invention I claim:

3. In assembling apparatus for closure caps, a table, parallel cap supporting channels mounted on and extending longitudinally of the table and arranged to support the caps at opposite side portions thereof, means to deliver caps to one end of and intermittently advance the caps along the channels, means operative during the periods of rest of the caps to sever disks from adhesive carrying webs and deliver the same to the caps supported in the channels, means arranged in advance of the adhesive disk severing and delivering means for supporting sealing disks in stacked formation above and at the side of each channel, means operative during the periods of rest of the caps to deliver sealing disks from said supporting means to said adhesive disk carrying caps in the channels, means for providing a zone having an elevated temperature through which the caps are moved as they are advanced along the channels from the position of receiving the adhesive disk to receiving the sealing disk to render the adhesive of the disks carried by the caps viscous, a rotatable head at the opposite end of the table arranged with an annular shelf to which the caps with sealing disks assembled therein are delivered from the channels, a pair of concentric and circularly arranged rows of spring influenced plungers carried by the head in and normally urged toward the closure receiving shelf, and means to position said plungers away from said shelf and retain them in such position for a predetermined portion of the rotation of the head to permit of the delivery of caps with sealing disks assembled on the shelf and the ejecting of the assembled closure caps from said shelf.

4. In assembling apparatus for closure caps of the class specified, a pair of parallel channels arranged to support the caps at the corrugated marginal portion for transport along the channels, a rotatable disk at one end of said channels, a cap delivery chute leading to said disk, means relative to which the caps on the disk are positioned by the rotation thereof operative to feed caps to the respective channels, and means to intermittently advance the caps in the channels.

5. Assembling apparatus for closure caps as claimed in claim 2, wherein the cap supporting channels comprise a pair of rails each constituting a cap supporting side member of a channel, and an intermediate rail to constitute the other cap supporting side member of the channels.

6. Assembling apparatus for closure caps as claimed in claim 2, wherein the means to continuously actuate said finger bars to engage the fingers in the rear of the successive caps supported in the channels, advance the caps in the channels and then laterally out of cap engaging position and rearwardly to position for movement to cap engaging position.

7. In assembling apparatus for closure caps of the class specified, a pair of parallel channels arranged to support the caps at the corrugated marginal portion for transport along the channels, a rotatable disk at one end of said channels, a cap delivery chute leading to said disk, means relative to which the caps on the disk are positioned by the rotation thereof operative to feed caps to

the respective channels, means to intermittently advance the caps in the channels, means operative in sequence with the cap advancing means to sever disks from an adhesive carrying web and deliver the severed disks to the successive caps in the channels, means arranged in advance of said adhesive disk severing and delivery means to support sealing disks in stacked formation in a plane above and at the side of each channel, means operative simultaneously with the disk severing and delivery means to deliver a sealing disk from each stack to said adhesive disk carrying caps in each channel, means to provide a zone having an elevated temperature through which the caps are passed in the transporting thereof in the channels from the adhesive disk severing and delivery means to the sealing disk delivery means to render the adhesive of the adhesive disks carried by the caps viscous, and means to which the caps with the sealing disks assembled therein are delivered from the channels to place the sealing disks under pressure in the caps for a predetermined interval of time.

8. Assembling apparatus for closure caps as claimed in claim 7, wherein the means to sever disks from an adhesive carrying web and deliver said disks to the caps in the channels comprises a support for a pair of rolls of adhesive carrying webs, a guideway for said webs extending transversely above the cap supporting channels, means operative simultaneously with the advancing of the caps to feed a predetermined length of the webs and return said feeding means to initial position during the periods of rest of the caps, and means operative during the periods of rest of the caps to sever a disk from each of the webs and deliver one of the severed disks to a cap in one channel and the other disk to a cap in the other channel.

9. Assembling apparatus for closure caps as claimed in claim 7, wherein the means to sever disks from an adhesive carrying web and deliver said disks to the caps in the channels comprises a support for a pair of rolls of adhesive carrying webs, a guideway for said webs extending transversely above the cap supporting channels, means to hold the webs in feed position during the return movement of the web feeding means, a pair of plungers one above each channel operative during the periods of rest of the caps and arranged to sever a disk from each web and deliver the severed disks to caps in each of the channels.

10. Assembling apparatus for closure caps as claimed in claim 7, wherein the means to sever disks from an adhesive carrying web and deliver said disks to the caps in the channels comprises a support for a pair of rolls of adhesive carrying webs, a guideway for said webs extending transversely above

the cap supporting channels, reciprocatory means to feed a predetermined length of each of the webs, means operative from caps in the channels to render either of said reciprocatory means active, means to hold the feed webs against retrograde movement by the return movement of the web feeding means, and a plunger above each of the webs and channels arranged and operative during the periods of rest of the caps to sever a disk from each web and deliver the disks to caps in each of the channels.

11. Assembling apparatus for closure caps as claimed in claim 7, wherein the means to support the sealing disks in stack formation in a plane above and at the side of the channels comprises supports, and tubular chutes in which the disks are stacked supported with the ends in spaced relation to the sealing disk support.

12. Assembling apparatus for closure caps as claimed in claim 7, wherein the means to deliver the sealing disks from the stacks to the adhesive disk carrying caps in the channels, comprises a pair of plungers, one superposed to each of the channels, and having movement toward and away from the channels, slides arranged at opposite sides and reciprocatory transversely of the channels in a direction toward and away from each other and operative during the advancing movement of the caps to deliver the lowermost sealing disks from the stacks and position the same relative to the plungers, and said plungers operative during the periods of rest of the caps to deliver the sealing disks positioned relative thereto to caps in the channels.

13. In assembling apparatus for closure caps of the class specified, parallelly arranged cap supporting channels, a rotatable disk arranged at the entrances to said channels, a chute to deliver caps to the disk, means relative to which the caps on the disk are aligned with the leading cap in line with the entrance to one chute and the alternate cap in line with the entrance to the successive channel, and means to deliver said first and alternate caps from the disk to the channels.

14. Assembling apparatus for closure caps as claimed in claim 13, wherein the means to deliver the caps from the disk comprises parallel plungers arranged in alignment with the entrances to the channels and normally yieldingly urged independently in a direction toward and to deliver caps from the disk to the channels, and means to positively move said plungers in reverse direction against the action of said yielding means.

15. In assembling apparatus for closure caps of the class specified, parallel channels arranged to support the caps at the flanges, means to feed caps to one end of said chan-

- nels, means operative in sequence with the cap feeding means to intermittently advance the caps in the channels and during the advancing of the caps in the channels assemble sealing disks therein, a rotatable head at the opposite ends of the channels arranged with an annular shelf to which the assembled closures are delivered from the channels, plungers carried by said head in concentric rows in superposed relation to the shelf and yieldingly urged in a direction toward the shelf for forcibly engaging the sealing disks in closure caps on said shelf, and means to move and hold the plungers in position away from the shelf against the yielding means for a predetermined rotation of the head to permit of delivery of the assembled closures from the channels to the head shelf and the ejecting of the closures therefrom. 16. Assembling apparatus for closure caps as claimed in claim 15, wherein the closures from one channel are delivered to the shelf and positioned relative to one of said rows 25 of plungers and the closures from the other channel delivered to the shelf and positioned relative to the other row of plungers. 17. Assembling apparatus for closure caps as claimed in claim 15, wherein one wall 30 of each channel is arranged with an extension to guide and position caps on the shelf in line with the plungers, and pivotally supported yielding means to retain the caps in operative relation to said channel extensions. 18. Assembling apparatus for closure caps as claimed in claim 15, wherein the head embodies an annular closure receiving shelf, rings superposed to the shelf and each other and arranged in concentric rows with the 40 plungers slidably mounted therein to extend above said rings, and the inner row of plungers being of greater length than the outer row, roller carrying studs fixed in and extending laterally and outwardly from the 45 plungers, superposed plate cams arranged in the paths of movement of and for engagement by the plunger rollers as they approach the channels by the rotation of the head to move and retain the plungers in position 50 away from the closure receiving shelf to permit of delivery of assembled closures to the shelf, and bars interposed between the shelf and the plate cams to engage and eject the closures from said shelf by the rotation of the head, said plunger rollers being adapted to ride off from said cam plates and engage the sealing disks in caps on the shelf positioned relative to the plungers. 19. Assembling apparatus for closure caps 60 as claimed in claim 15, wherein the head embodies a shelf for receiving caps with sealing disks assembled therein from the channels and rings superposed to said shelf and each other having perforations therein 65 in which the plungers are slidably mounted, and the plungers have projections extending laterally and outward therefrom, adjustably mounted cam plates for engagement of the plunger projections by the rotation of the head to move the plungers 70 away from the shelf and retain them in said position for a predetermined rotation of the head to permit of ejection of closures from the shelf and the delivery thereto of assembled closures from the channels, and the plungers are adapted to engage with assembled closures on the shelf as the plunger projections ride off from said cam plates, and means to adjust said cam plates relative to the head and thereby control the riding of the plunger projections off from the cam plates in the rotation of the head. 75 Signed at the city of New York, in the county of New York, and State of New York, this 24th day of February, 1928. 80 JOHN A. JOHNSON. 85 90 95 100 105 110 115 120 125 130
